INVENTOR:
GEORGE L. BRIDGE.

BY Lawrence C. Kingsland

ATTORNEY.

UNITED STATES PATENT OFFICE

2,149,835

STOVE

George L. Bridge, Ladue Village, Mo.

Application March 13, 1937, Serial No. 130,682

2 Claims. (Cl. 126—58)

The present invention relates generally to stoves, and more particularly to a device adapted to be employed in combination with a stove to increase the heating efficiency thereof.

5 An object of the present invention is to provide, in combination with a stove, a device adapted to increase the heating efficiency of the unit.

10 Another object is to provide, in combination with a stove, a device which is adapted to control the path of travel of the heated gases and air to the flue.

15 Another object is to provide a device adapted to be used in combination with a stove which controls the path of travel of heated gases and air to the flue.

20 Another object is to provide a device which is adapted to be employed as a dome or top for a stove for the purpose of increasing the heating efficiency of the unit.

25 Another object is to provide a stove which includes means for controlling the path of travel of the heated gases and air to the flue.

Another object is to provide a stove which includes means for optionally increasing the heating efficiency of the unit.

Other objects and advantages will appear from the following description, taken in conjunction with the accompanying drawing, in which

Fig. 1 is a perspective of a casing which is 30 adapted to enclose a stove of a kind to include the instant invention as an integral or attached part.

Fig. 2 is an enlarged section on the line 2—2 of Fig. 1 showing a stove including a preferred embodiment of the present invention mounted within the casing.

35 Fig. 3 is a section on the line 3—3 of Fig. 2.

Fig. 4 is a section on the line 2—2 of Fig. 1, showing in open position a plate damper which forms a part of the instant invention.

40 Referring to the drawing more particularly by reference numerals, 10 indicates generally a casing which is adapted to enclose a heating unit, such as a stove. The casing 10 includes a base 11 having legs 12, and a superstructure 13 comprising side walls 14, a rear wall 15, a panelled front wall 16, and a top 17. The specific details of the casing form no part of the present invention.

45 A stove generally designated 20 is mounted within the casing upon the base 11. It includes a lower section 21, an intermediate section or fire pot 22, and an upper section 23. The lower section 21 and the intermediate section 22 are of conventional design and form no part of the present invention.

50 A preferred embodiment of the present invention

5 includes a dome or top superposed on the upper section 23 and is generally designated 25. The dome or top 25 is shown as integral with the upper section 23, but it may be constructed as a separate unit. The dome 25 includes an exterior 5 wall 26 which is shown as of elliptical configuration, although other forms may be employed, and a top wall 27. The exterior wall 26 includes integral therewith outwardly extending heat radiating fins 45 (Fig. 3) and an opening 46, which is 10 disposed in a position at the rear of the stove. An interior wall 28 depends from the top wall 27 and is likewise of an elliptical configuration, as is shown in Fig. 3. The wall 28 terminates at 29 and 30, thereby forming an opening 31. A top plate 15 33 is formed integrally with the upper section 23. The top plate 33 has an opening 34 therethrough of a configuration to conform to the outline defined by the wall 28.

15 The top plate 33 also includes an opening 35 20 which is closed by a damper plate or trap door 36. The damper 36 includes apertured lugs 37 through which extends and to which is fixed a rod 38 which is journaled in apertured lugs 39 integral with the upper section 23. A bar 40 (Fig. 3) is pivotally 25 connected at one end to a right angular extension 41 of the rod 38 and includes adjacent its free end notches (not shown) which are adapted to cooperate with an edge of an opening in the rear wall 15 of the casing 10. A handle 42 is connected 30 to the bar 40 for the purpose of manipulating the damper 36. This construction is shown in detail in my co-pending application Serial No. 130,683, filed March 13, 1937. A pipe section 47 is connected to the exterior wall 26 to cooperate with the 35 opening 46.

Operation

The operation of the invention is readily apparent from a perusal of the foregoing description, taken in conjunction with the accompanying drawing. Referring to Figs. 2 and 3 in which the damper 36 is shown in closed position, it is clear that the heated gases and air follow the path indicated by the arrows A through the opening 34 and the opening 31, and thence the optional paths between the walls 26 and 28 indicated by the arrows B and C and on out the pipe section 47 to the flue. By forcing the heated gases and air to follow this lengthy path, the 50 heat is retained longer in the stove and the efficiency is thereby greatly increased. The heat radiating surfaces of the stove are considerably increased by the fins 45 and cap 25.

55 When it is desired to pass the heated gases and

air by the shortest path to the flue, the damper 36 is opened to the position shown in Fig. 4, or to some intermediate position, thereby providing a direct draft. This, of course, may be desirable at 5 those times when there is insufficient draft to carry the heated gases around the long path.

It is thus apparent that there has been provided a device adapted to be used in combination with a stove which increases the heating efficiency 10 of the unit both by maintaining the heated gases and air a longer time within the unit and by providing additional heat radiating surfaces.

It is to be understood that the foregoing description and accompanying drawing have been 15 given by way of illustration and example and not for purposes of limitation, the invention being limited only by the following claims.

What is claimed is:

1. A stove comprising an upper section and a 20 dome, said upper section including a top plate having an opening therethrough, said dome including an exterior wall having an aperture therein and an interior wall defining the opening in the plate and having an opening therein, said plate 25 having an additional opening adjacent the opening in the exterior wall, and a plate damper op-

eratively associated with said last-named opening and adapted to be selectively opened or closed, said construction permitting heated gases and air to pass directly to the flue through the second plate opening and the exterior wall opening when the damper is open, and said construction forcing the said heated gases and air to travel successively through the first enumerated plate opening, the interior wall opening and the exterior wall opening when the damper is closed. 5

2. A stove comprising an upper section and a dome, a horizontal partition plate disposed between the upper section and the dome substantially coextensive with the same, a centrally disposed opening in the plate, said dome including a 15 single circular channel, the inner wall of which substantially defines the said opening and the outer wall of which comprises the exterior vertical wall of the dome, an opening in the inner wall and a flue opening in the outer wall, said latter 20 two openings being spaced at 180 degrees, and a flap damper pivotally connected to said plate adjacent said outer wall opening and between said walls to provide an optional full direct draft. 25

GEORGE L. BRIDGE.
